UNITED STATES PATENT OFFICE.

FREDRICK J. RIKER AND CLARENCE E. BLEICHER, OF DETROIT, MICHIGAN, ASSIGNEES TO CHRYSLER CORPORATION, OF DETROIT, MICHIGAN, A CORPORATION OF DELAWARE.

OVEN CONSTRUCTION.

Application filed March 8, 1928. Serial No. 265,342.

This invention relates to an oven construction and more particularly to a closure for the open end thereof.

In ovens particularly adapted for baking the enamel on vehicle bodies the open end thereof is usually provided with a door or is sometimes left open and the bodies on a continuously moving conveyor are taken from the oven. A great amount of heat is wasted in constructions where the end of the oven is left open or where a door is used which must necessarily be left open while bodies are being removed. It is therefore an object of this invention to provide a construction whereby the open end of the oven may be closed while the bodies are being removed from the oven.

Other objects and advantages will more fully appear from the following description taken in connection with the accompanying drawings in which:

Fig. 1 is a sectional view through an oven showing in a diagrammatic way my improved closure for the open end of the oven.

Fig. 2 is a view corresponding to Fig. 1 in which a body is being removed from the oven with the opening closed.

Fig. 3 is an end view of Fig. 2.

Fig. 4 is a fragmentary view showing a means for engaging the closure with one of the conveyors.

Referring to the drawings, we have shown an oven 10 having therein a track 12 which receives a plurality of trucks 14 which are adapted to be continuously forced through the oven. Bodies 16 have been shown on the trucks.

Near the open end of the oven, we have provided a closure 18 which consists of a framework supported on wheels 20 adapted to move on a track 22. The framework comprises side walls 24 which fit closely to the inner wall of the oven and are of sufficient length to extend beyond both ends of a vehicle body on the truck 14. The ends are open and a slideable curtain 26 is adapted to close one end and the top of the framework. The track 22 extends part way into the oven and beyond the open end thereof so that the closure 18 may be entirely received in the oven or may be drawn outside of the oven. A stop 28 has been shown to block the closure when it is drawn from the oven so that the rear end thereof is not removed.

As shown in Fig. 1 the curtain 26 is in position to close the forward end and top of the closure and the closure is entirely within the oven enclosing on two sides and the forward end the first truck and the body thereon. As the truck is pushed forward the closure is carried with the truck to a position shown in Fig. 2. The curtain may then be raised whereupon it passes rearwardly and downwardly over rollers 27, closing the rear end and top of the closure. The truck in the closure may then be removed through the open end of the closure and the oven remains closed by the curtain at the rear end of the closure between the first and second trucks. After the first truck and body have been removed from the closure the curtain is then drawn down at the forward end of the closure and the closure shoved back into the oven enclosing the next body on two sides, top and forward end. It will be obvious that the forward end of the oven will likewise be closed.

As a means for positioning the closure with respect to the body and its truck we have provided a stop mechanism which comprises a lever 30 pivoted to one of the side walls as at 32 and having an inwardly projecting abutment 34 which engages a portion 36 of the truck 14. The lever 30 has a handle 38 which projects beyond the forward end of the closure and a spring 40 normally holds it in position against an abutment 42 so that the abutment 34 engages the portion 36. Thus it will be understood that when the closure is shoved in the oven, the stop 34 being in its normal position, it will engage the portion 36 of the truck and limit its movement. The continuous movement of the trucks will cause the closure to be carried with the truck and it will be forced out of the oven with the body. The handle 38 is pressed downwardly to move the abutment 34 out of the path of the portion 36 on the truck thus permitting independent movement between the truck 14 and the closure 18.

It will be obvious that various changes may be made in the arrangement, combination and construction of the various parts of our improved device without departing from the spirit of our invention, and it is our intention to cover by our claims such changes as may be reasonably included within the scope thereof.

What we claim is:

1. A closure for the open end of an oven comprising a pair of spaced side walls adapted for movement into and out of the open end of the oven, rollers at the upper corners of said side walls, and a slidable cover over said rollers adapted to close the opening between said side walls at the top and one end thereof. 5
2. A closure for the open end of an oven comprising a pair of spaced side walls adapted for movement into and out of the open end of the oven, and a curtain having a portion to close the forward open end between said side walls and a portion to close the rear open end between said side walls, said portions being arranged to permit the closing of one end by the opening of the opposite end. 10
3. A closure for the open end of an oven comprising a pair of spaced side walls connected together, means for closing the opening at the top between said side walls and for alternately closing and opening the space at the ends between said side walls. 15
4. In a closure for the open end of an oven comprising in combination, an oven having a top and side walls, guiding means within said oven, a plurality of objects to be heated within said oven movable on said guiding means, a pair of connected walls adjacent the side walls of said oven adapted for movement into and out of the open end of said oven, and means for closing one end of the opening between said walls, for closing the top opening between said side walls, and for closing the opposite end of the opening between said side walls by the movement of said means to open the first mentioned end opening. 20
5. In a closure for the open end of an oven comprising in combination, an oven having a top and side walls, guiding means within said oven, a plurality of objects to be heated within said oven movable on said guiding means, an enclosure for one of the objects adjacent the open end of the oven, movable with the ob- 25
- ject, and means for opening one end of the enclosure by closing the opposite end. 45
6. A closure for the open end of an oven comprising in combination, an oven having a top and side walls, guiding means within said oven, a closure for the open end of said oven having a pair of side walls adapted for movement into and out of the open end of said oven, and means on one of said last named side walls for engagement with an object movable through said oven on said guiding means. 50
7. A closure for the open end of an oven comprising in combination, an oven having a top and side walls, guiding means within said oven, a closure for the open end of said oven having a pair of movable side walls and a top covering for the space between said movable walls, means on one of said movable walls, for engagement with an object movable through said oven on said guiding means, means for permitting the disengagement of said last named means, and means for alternately opening and closing the space between the movable side walls at opposite ends thereof. 55
8. An oven of the class described comprising a pair of spaced side walls and a top therefor, guiding means within said oven adapted to conduct objects to be heated through said oven, a closure for the open end of said oven adapted for movement into and out of said oven, means carried by said closure for engagement with an object to be heated within said oven, and means for permitting the disengagement of said last named means for removing the object through said closure. 60
9. An oven of the class described comprising a pair of side walls and a top therefor, a closure for one end thereof adapted for movement into and out of said oven, and means on said closure for permitting the removal of an object to be heated through said closure. 65
